Primary Examiner — Michael C Stout*Assistant Examiner* — Fitzgerald L Butac(74) *Attorney, Agent, or Firm* — Morris, Manning & Martin, LLP; Daniel E. Sineway, Esq.; Adam J. Thompson, Esq.(57) **CLAIM**

The ornamental design for a boring tool handle, as shown and described.

DESCRIPTION

FIG. 1 is a top, front, right perspective view of a boring tool handle;

FIG. 2 is a bottom back perspective view thereof;

FIG. 3 is a left side elevation view thereof;

FIG. 4 is a right-side elevation view thereof;

FIG. 5 is a front elevation view thereof;

FIG. 6 is a back elevation view thereof;

FIG. 7 is a top plan view thereof; and,

FIG. 8 is a bottom plan view thereof.
